UNITED STATES PATENT OFFICE.

WILLIAM J. GETSINGER, OF LOS ANGELES, CALIFORNIA.

COLLAR.

1,413,470.

Specification of Letters Patent. Patented Apr. 18, 1922.

Application filed December 6, 1920. Serial No. 428,675.

To all whom it may concern:

Be it known that I, WILLIAM J. GETSINGER, a citizen of the United States, residing at Los Angeles, in the county of Los Angeles and State of California, have invented new and useful Improvements in Collars, of which the following is a specification.

It is the object of this invention to provide a collar having stiffening means, and means 10 cooperating therewith for retaining the front flaps of the collar properly overlapped in order that the collar will present a neat appearance.

The invention will be readily understood 15 from the following description of the accompanying drawings, in which:

Figure 1 is a perspective view showing the collar when fastened.

Fig. 2 is a view of the collar showing the 20 flap portion folded back from the neck band.

Fig. 3 is a plan view of the stiffener.

Fig. 4 is a detail perspective view of one end of the stiffener.

25 Fig. 5 is a detail section on the line 5—5 of Fig. 2.

The collar having the improved stiffening means is of the so called soft collar type, and comprises a neck band formed of inner 30 and outer layers 1 and 2, and a folding flap portion 3 adapted to be folded down upon the neck band. The overlapping front flaps of the neck band are shown at 4 and 5, the flap 4 being adapted to be overlapped by the flap 5. These flaps are provided with the usual button-holes 6 for a collar button, and the flap 5 is also provided with a button-hole 7 adjacent the upper edge of the same, which in collars as heretofore constructed was received over a button 35 adjacent the upper edge of flap 4 in order to assist in retaining the collar in proper position when fastened.

In the improved construction a stiffening strip 8 formed of celluloid or the like is inserted between the layers of the neck band for stiffening the latter. This stiffener may be inserted through an opening 9 provided in the inner layer 2 of the neck band in 40 alinement with the rear button-hole 10, and this stiffener extends substantially the length of the neck band so as to terminate short of button-hole 7. The stiffener may

be cut away as shown at 11 in order not to overlie the button-holes 6.

55

In my improved construction when the collar is fastened, the button-hole 7 is engaged by the stiffener 8 at the end flap 4 of the neck band, and for this purpose a button-hole 12 is provided in the inner layer of the 60 neck band adjacent the upper edge of flap 4 in a position to align with button-hole 7 when the collar is fastened.

The stiffener 8 carries a member which projects through the button-hole 12 and is 65 engaged by the button-hole 7. This member may comprise a wire loop 13 having its ends received through apertures 14 in the stiffener 8, and bent back upon the stiffener.

The loop portion of the wire extends outwardly through one of the openings 14 and through button-hole 12, and is then reversely bent in order to form a hook 15. When the collar is fastened this hook is engaged by the button-hole 7, so that the collar includes a neck band stiffener, which at one end is engaged by the overlapping flap of the opposite end of the collar. By this arrangement the collar is held in upright position at all times and will thus present a neat appearance.

75

Various changes may be made without departing from the spirit of the invention as claimed.

What is claimed is:

85

1. A collar including a neck band forming a pocket, a stiffener in said pocket, an engaging member carried by said stiffener and projecting transversely through said neck band at one of its overlapping end flaps, said engaging member arranged to engage the overlapping flap at the opposite end of the neck band.

90

2. A collar including a neck band forming a pocket, a stiffener in said pocket, one of the overlapping end flaps of the neck band having a button-hole, and an engaging member carried by the stiffener and projecting transversely through the neck band at the other overlapping end flap, said engaging member being received in said button-hole.

95

3. A collar including a neck band forming a pocket, a stiffener in said pocket, a hook projecting transversely from said stiffener through said neck band at one of its overlapping end flaps, said hook

100

105

being arranged to engage the overlapping flap at the opposite end of the neck band.

4. A collar including a neck band forming a pocket, a stiffener in said pocket, a wire looped through said stiffener to form a hook projecting from said stiffener through said neck band at one of its overlapping end

flaps, said hook being arranged to engage the overlapping flap at the opposite end of the neck band.

10 In testimony whereof I have signed my name to this specification.

WILLIAM J. GETSINGER.
